UNITED STATES PATENT OFFICE.

EDWARD F. MILLARD, OF MARINETTE, WISCONSIN.

WOOD-GRINDER.

SPECIFICATION forming part of Letters Patent No. 320,574, dated June 23, 1885.

Application filed January 31, 1885. (No model.)

To all whom it may concern:

Be it known that I, EDWARD F. MILLARD, a citizen of the United States, residing at Marinette, in the county of Marinette and State of Wisconsin, have invented a new and useful Improvement in Wood-Grinders, of which the following is a specification, reference being had to the accompanying drawings.

My invention relates to an improvement in wood-grinders for making paper-pulp; and it consists in the peculiar construction and combination of devices that will be more fully set forth hereinafter, and particularly pointed out in the claims.

15 In the accompanying drawings, Figure 1 is a vertical longitudinal sectional view of a machine that embodies my invention. Fig. 2 is a top plan view of one of the hoppers, showing the follower therein. Fig. 3 is a detailed view of one of the side plates of the hoppers.

20 A represents a grinding-stone, and B represents a series of hoppers, which are arranged around the upper edge of the stone in the form of an arc, as shown. The sides of these 25 hoppers are formed by the plates C, which are provided at their centers on their opposing faces with the vertical ribs D, which are adapted to receive and guide the grooved anti-friction wheels E, that are journaled in blocks F, that are bolted to the upper sides of the 30 followers G. Near the outer edges of the plates C, on their opposing faces, are formed the projecting flanges H, having inclined inner edges, I. These flanges approach nearest 35 to each other at the upper sides of the plates, and gradually recede from each other as they approach the lower sides of the plates, as shown.

30 The billets or blocks of wood which are to be ground by the stone are placed in the hoppers, and are prevented from coming in contact with the inner sides of the plates C by means of the inclined edges of the flanges H, and thus friction between the blocks of wood 45 and the inner sides of the plates is prevented.

When enough of the wood has been ground away to clear the blocks from the flanges H, the followers, which bear upon the upper sides of the blocks, hold said blocks against lateral movement, and thus prevent the blocks from 50 coming in contact with the flanges H of the side plates of the hoppers while being ground.

By means of this invention I am enabled to feed the blocks of wood to the grindstone without friction between the blocks and the 55 side plates, as will be very readily understood.

Having thus described my invention, I claim—

1. The combination of a grindstone with the hoppers having projecting flanges on their 60 opposing sides, for the purpose set forth, substantially as described.

2. The combination of a grindstone with the hoppers having inclined projecting flanges on their opposing faces, and followers that are 65 adapted to move in the hoppers, substantially as described.

3. The combination of a grindstone with the hoppers having their sides formed of plates, which plates are provided with a vertical central rib or groove on their opposing faces and with inclined flanges, and followers 70 that are guided by the vertical ribs or grooves, substantially as described.

4. The combination, with a grindstone, of 75 the hoppers having their sides formed of plates, which plates are provided with ribs or grooves and with inclined flanges on their opposing faces, and followers having anti-friction wheels, which engage with the ribs or 80 grooves, for the purpose set forth, substantially as described.

In testimony that I claim the foregoing as my own I have hereto affixed my signature in presence of two witnesses.

EDWARD F. MILLARD.

Witnesses:

JOHN B. FAIRCHILD,
A. A. FAIRCHILD.
